APPARATUS FOR CONVEYING AND BUNDLING NEWSPAPERS AND THE LIKE

Loye T. Lovette, Dayton, Ohio

Application June 4, 1935, Serial No. 24,892

12 Claims. (Cl. 100—31)

This invention relates to new and useful improvements in apparatus for conveying and bundling newspapers and the like.

One of the principal objects of my invention is the provision of automatic means to receive folded newspapers from a printing press and deliver them in stacks of a predetermined number to a bundling device.

Another important object of my invention is the provision of automatic means for receiving stacks of newspapers and fashioning them into compact bundles for their subsequent delivery from the bundling device.

In the newspaper printing art at present, the folded newspapers are deposited by the press upon conveyors which carry them to tables where they are manually wrapped, tied into bundles and labeled for further dispatch. When the papers are deposited upon the conveyors, cam means are utilized to dis-arrange or mis-align one of the newspapers. Each mis-aligned paper is indicative that a certain number of newspapers are deposited between it and the next preceding mis-aligned newspaper, usually fifty papers.

It is one purpose of this invention to provide means for placing the newspapers from the delivery fan of the printing press, in a stack upon the conveying mechanism. I utilize the cam means above referred to to trip the actuating mechanism of the conveyor to advance the accumulated stack and receive the following newspapers in a subsequent stack. As the stacks are advanced, they are finally positioned beneath the binding mechanism. The latter now surrounds the stack of newspapers with a single strand of wire, the adjoining ends of which are united and severed from the supply source. Following the severing of the wire strand, the completed bundle of newspapers is delivered from the bundling mechanism, ready for shipment.

Other important and incidental objects of my invention will be brought out in the following specification and particularly set forth in the subjoined claims.

In the accompanying drawings illustrating my invention, Figure 1 is a side view of the newspaper conveyor and bundling mechanism. Figure 2 is a view of the receiving end of the device. Figure 3 is a view of the delivery end of the same. Figure 4 is a longitudinal sectional view taken on the line 4—4 of Figure 3. Figure 5 is a detail view of the wire severing mechanism. Figure 6 is a sectional view taken through the shuttle

and shearing mechanism on the line 6—6 of Figure 5. Figure 7 is a cross sectional view of the shuttle, showing the feeding collet and retrieving mechanism. Figure 8 is a detail view of the binding head, showing the wire receiving jaws. Figure 9 is a cross sectional view, with parts in elevation of the wire receiving jaws, taken on the line 9—9 of Figure 8. Figure 10 is a detail view of the cam actuated mechanism for twisting and severing the binding wire. Figure 11 is a detail view of the cam actuated means for advancing the conveyor mechanism step by step. And Figure 12 is a sectional view of the rear end of the shuttle tube, on the line 12—12 of Figure 1.

Referring to the accompanying drawings for a detailed description of my invention, the numeral 1 designates a gear side frame having a top horizontal member 2, a bottom horizontal member 3, a front vertical member 4 and a rear vertical member 5. (See Figure 1.) Opposite the frame 1 is a similar frame 6 that is joined with the former by cross supports 7 positioned intermediate the ends of the side frames.

Journalized in the front vertical members 4 of the side frames is a conveyor belt drive shaft 8 to which are keyed spaced, conveyor belt sprockets 9, 9. The rear vertical members 5 carry another shaft 10 upon which rear conveyor belt sprockets 11, 11 are keyed. Passing around each pair of aligned sprockets 9 and 11 is an endless conveyor chain 12. Now, when the shaft 8 is rotated, these chains 12 will advance simultaneously.

Secured to the outer face of each chain 12 are spaced leading stack fingers 13. Each of these fingers is formed with a forwardly curved outer end 14, carrying a barbed finger 15. Spaced rearward of the stack finger 13 is another stack finger 16, shorter than the finger 13 and spaced sufficiently from it to receive between the spaced fingers a folded newspaper. The respective fingers 16 and 13 are spaced closely together in order to provide the maximum number of stack spaces upon the chain.

Above the shaft 8, the side frames 1 and 6 are formed with vertical extensions 17 to support a cross bar 18. Projecting upwardly from this bar 18 are diverter fingers 19. It is the function of these fingers to divert the folded newspapers from the newspaper press delivery fan positioned above the conveyor.

As shown in Figure 1, the delivery fan 20 which is an integral part of the conventional printing press, is formed of a series of spaced

octagonal discs 21 to whose flat sides blades 22 are secured. When the press is in operation, the fan 20 will be operated in synchronism with the press and the folded edges of the newspapers 5 will be received between the blades 22 and against the discs 21.

The fan being rotated clockwise as viewed in Figure 1, the newspapers carried thereby will be engaged by the diverter fingers 19, which will 10 force them from the fan and stack a required number of them upon the conveyor between the fingers 13 and 16. The method of advancing the conveyor chains, after a pre-determined number of newspapers have been deposited thereon, will 15 now be described.

As previously described, a cam is utilized to misalign one of the newspapers as it is deposited upon the conventional conveyor mechanism. This is accomplished by a depression in the 20 periphery of the cam, which, for each revolution of the latter, causes a cam follower to momentarily engage that newspaper passing beneath it to mis-align it.

Referring now to Figure 1, I have shown this 25 cam, which will be designated 23, positioned near the fan 20 and rotatable upon a shaft 24. Instead of the method previously employed, I have utilized this cam to actuate a drive mechanism for advancing the conveyor chains.

30 Secured to the end of the shaft 24 adjacent the outer face of the frame 1, is a four-toothed gear 25 of a conventional Geneva type. Positioned below the gear 25 is a pin disc 26 and lock plate 27 forming part of the Geneva gear system. Secured to the inner face of the lock plate 27 is a pinion 28. This pinion, disc 26 and plate 27 are 35 keyed together for rotation upon a stub shaft 29 secured to the side frame 1.

Below the shaft 29 is another stub shaft 30, 40 one end of which is journaled in the frame 1 and its outer end in an outboard bearing 31. Keyed to the shaft 30 is a large gear 32 that meshes with the pinion 28. Keyed to the outer end of the shaft 30, adjacent the bearing 31, is a drive plate 33.

The plate 33 has formed therein, adjacent its periphery, a square hole 34 parallel with the axis of the shaft 30. Positioned within the hole 34 and slideable therein is a dog 35 whose outer face 50 has formed therein a square recess 36. (See Figures 2 and 11.)

Secured to the inner face of the bearing 31 is a cam plate 37 having upon its periphery a spiral cam 38. This spiral cam 38 is adapted to enter 55 the recess 36 when the plate 33 is rotated, as will presently be described. (See Figure 11.) Free- 60 ly mounted upon the shaft 30 is a sprocket 39 having a long hub extension 40. This sprocket is rotated by a drive chain 41 from a like sprocket 42 secured upon a main drive shaft 43 positioned at the rear end of the machine and later to be described.

The sprocket 39 has formed in its web adjacent its periphery, a square hole 44 which, when it is 65 rotated, will be brought into alignment with the recess 36. Now there is provided on the outboard bearing 31 spaced lugs 45, between which there is pivotally mounted a pawl 46. Secured to the outer end of this pawl 46 is a link member 47 70 whose upper end is pivotally connected to one end of a lever arm 48. (See Figures 1, 2 and 11.)

The lever arm 48 is pinned to one end of a short shaft 49 journaled in a rearward extension of the frame 1. Secured to the opposite end of 75 the shaft 49 is a cam follower arm 50 whose outer

end is in contact with the cam 23. When the cam 23 revolves, the cam follower arm 50 will rise as it enters the cam depression 23a, and the pawl 46 will force the dog 35 into the recess 44 and the recess 36 will be engaged by the spiral 5 cam 38.

Upon the continued rotation of the sprocket 39, the dog 35 will be withdrawn from the recess 44 at the completion of a single revolution of the plate 33. During the single revolution of this 10 plate 33 and the gear 32 connected with it, the Geneva gear mechanism consisting of the gear 25, disc 26 and plate 27, will cause the sprockets 9, 9 to make a quarter revolution. This quarter revolution will advance the conveyor chains sufficiently and accurately to position the succeeding stack fingers beneath the delivery fan, and the preceding stack of newspapers beneath the binding head, which will presently be described.

Formed rearward of the rear vertical members 20 5 of the side frames 1 and 6, are short frame structures 51 and 51a, in whose rearward vertical struts 52 the main drive shaft 43 is journaled. Secured to the shaft 43 is a conventional clutch mechanism 53 manually operated 25 by a lever arm 54.

Attached to the free side of the clutch 53 is a sprocket 55 which is adapted to be driven by a sprocket chain 56 from an electric motor 57. (See Figure 1.) It is the purpose of this motor 30 30 to drive to complete the binding of the newspapers upon the conveyor when the press is not in operation.

Also secured to the shaft 43 is another clutch 35 mechanism 58 of the positive drive type. The free side of this clutch has secured thereto a sprocket 59 to receive a chain 60, (see Figure 3). This chain also passes around another sprocket 61 on the shaft 24 for the cam 23. (See Figure 1.)

Normally the conveyor and binder are driven from the cam shaft 24 in order that all of the operations thereof will be maintained in a correctly timed relation with the press, the latter operating at varying speeds dependent upon the 45 size of the edition of the newspaper being run.

Before describing the various intermittent drives for the bundling device, the various operations thereof will be described.

Coincident with the positioning of a stack of 50 papers to be bound beneath the binder, the feed shuttle advances a strand of wire to the opposite side of the binding yoke to be held by a gripping and releasing device on said opposite side, the feed shuttle being withdrawn. The yoke is now drawn 55 downward, straddling the stack of newspapers and drawing additional wire through the feed collet to encompass three sides of the stack. When the yoke is held down, the opposite side of the shuttle will advance to grip the end of the 60 wire strand held in the forward side of the binding head and draw it rearwardly beneath the stack of newspapers.

As soon as the retrieving shuttle is fully withdrawn, the free end of the wire, gripped in the 65 retrieving shuttle, and the wire in the feeding collet are twisted together by a simultaneous rotation of both shuttles. After the strands are twisted together, the ends are severed and the binding head raised. With the raising of the 70 binding head, the conveyor belt is advanced to discharge the bound newspapers and position a succeeding stack beneath the binding head.

Each of the rear vertical supports 5 of the side frames 1 and 6 projects above the top members 75

2, and has formed therein an elongated slideway 62 for a cross head 63. At each side the cross head 63, where it is supported within the slideway, is formed with a depending flange 64 joined by a transverse rib 65 with the center of the cross head. Above the cross head proper the side flanges are formed rearwardly to provide bearings 66, 66 for the shuttle actuating shafts 67 and 68.

10 Below the bearings 66, 66, and between the side frames 1 and 6, there is provided a rearwardly extending bearing 69 integral with the cross head and adjacent the side frame 1, for a short horizontal shaft 69^a. Adjacent the side frame 6 is a 15 similar bearing 70 for another short horizontal shaft 70^a. Immediately below the bearing 69, and likewise integral with the cross head, is another bearing 71 for a vertical shaft 72. Also below the bearing 70 is a bearing 73 for another vertical 20 shaft 74 adjacent the side frame 6.

On the rear side of the machine the cross head 63 has projecting therefrom a short stud 75 that receives thereon a link 76. The lower end of the link 76 is pivotally connected to the free end of a 25 crank 77 that is rotatable with a shaft 78 to which it is keyed. The shaft 78 is journaled in the rear vertical member 5 of the side frame 1, and has secured thereto a gear 79 by which the 30 shaft is rotated through means later to be described.

When the shaft is rotated to bring the crank 77 to the position shown in Figure 1, the cross head 63 will be raised, and when the shaft is rotated 180 degrees the cross head will be lowered.

35 The cross head and shuttle mechanism will now be described. At the center of the cross head 63 I have provided a cylindrical boss 80, bored out to receive therein the hub extension 81 of a worm gear 82. The hub is maintained 40 within the boss 80 by a retainer collar 83 secured to the rear end thereof. (See Figure 6.)

The hub extension 81 of the gear 82 is machined to receive therein the forward end of a 45 shuttle tube 84, that does not extend entirely through the hub. In front of the end of the tube 84, the hub 81 is counterbored and formed with square serrations 85. Slidably positioned within the shuttle tube 84 is a semi-circular feed shuttle 86 and a semi-circular retrieving shuttle 50 87. The shuttles 86 and 87 at their forward ends are provided with semi-circular serrated flanges 86^a and 87^a which, when the respective shuttles are fully withdrawn, will be received within the serrations 85.

55 The semi-circular feed shuttle 86 has therein an axial passage 88, which, adjacent the front end of the former, terminates in a short tapering bore 89 and a smaller straight bore 90. Positioned within the bore 90 is a feed collet 91, whose outer end projects slightly beyond the face of the shuttle. At its rear end the collet is formed with a tapering head portion 92 which is slotted in a conventional manner to render it yieldable when forced into the tapering bore 89.

65 Extending axially of the collet is a passage for the binding wire that projects forwardly through the shuttle, and a slideable tube 93 positioned in the passage 88 rearward of the shuttle.

The rear end of the shuttle tube 84 is secured 70 within a sleeve 94. Extending rearwardly from this sleeve are parallel flanges 95, 95 between which spring tensioned jaws 96, 96 are positioned. The purpose of these jaws 96, 96 is to permit the free withdrawal of the binding wire and at the 75 same time to prevent the retroactive movement of

the wire when the collet is released. (See Figure 3.)

When the feed shuttle is moved rearwardly to the rearward limit of its travel, the tube 93 will strike the jaws 96, 96 and force the collet 91 forwardly into the tapering bore 89 to lock the wire 5 therein.

The retrieving shuttle 87 has in its forward end a square recess 97, rectangular in cross section and whose opposite narrow faces 97^a, 97^a are 10 tapered rearwardly. Extending from the bottom of the recess 97 to the rear end of the shuttle is an aperture in which is positioned a slideable rod 98. (See Figure 7.)

Positioned within the recess 97 is a pair of 15 hinged, spring tensioned jaws 99, whose opposite faces bear against the tapering faces 97^a, 97^a of the retrieving shuttle. Now, when the shuttle reaches its rear-most position, the rod 98 will be forced forwardly to force the jaws out of the 20 tapering recess 97, whereupon they will remain open.

Each of the shuttles 86 and 87, adjacent its rearward end, has formed in its semi-circular periphery a groove or recess 100, which, when the 25 shuttles are fully withdrawn into the tube 84, forms a continuous circular recess. Positioned in each recess 100 is a semi-circular yoke 101 having at its center an outwardly projecting radial stud 102. (See Figure 12.) Each of the 30 studs 102 is slideable in an elongated slot 103 in the opposite side walls of the shuttle tube 84. When these studs 102 are moved axially of the tube 84, a respective shuttle will be projected, and when the shuttles are fully withdrawn into the 35 tube 84, their rotation is possible by virtue of the alined recesses 100—100. Extending upwardly from the sleeve 94 are spaced arms 104, 104 upon which a supply of binding wire 104^a is supported.

Secured to the cross head 63, and extending 40 upwardly from the boss 80, is an inverted U shaped binder yoke 105, preferably of channel shape in cross section and reinforced with web plates 106, secured to the side flanges of the yoke proper. In the forward depending end of 45 the yoke, I have provided an aperture 107 behind which there is positioned a chuck mechanism 108 to receive and hold the end of the wire strand as it is delivered by the feed shuttle 86. This chuck mechanism 108 consists of a pair of 50 wide jaws 109 and 110, positioned horizontally and in substantial alinement with the feed shuttle the collet. (See Figure 9.)

The jaw 109, which functions as a release jaw, is positioned within a rectangular recess 111 and 55 at a slight angle with the axis of the shuttle. At its inner end the recess 111 terminates in a larger aperture 112 in which a strong spring 113 acts to force the jaw out of its inclined recess toward and into engagement with its companion 60 jaw 110. The jaw 110, which is slightly longer than, and extends beyond, the jaw 109, is also received within a rectangular recess 114. This recess is also inclined, with respect to the recess 111 and at such an angle that, when the jaw 110 65 is forced into its recess, it will co-act with the jaw 109 to firmly grip the strand of wire. Like the recess 111, the recess 114 terminates in a larger aperture, 114^a, in which another spring 115, lighter than the spring 113, tends to force the 70 jaw 110 out of its inclined recess and out of engagement with the jaw 109.

The angle of the recesses receiving the jaws is such however, that, after the jaw 110 is forced into its recess, it will not be forced out by the 75

spring 115 until the jaw 109 is forced into its recess, due to their wedge action.

Projecting from the face of the release jaw 109 is a finger 116 which, when the retrieving shuttle advances to pick up the end of the wire, will be engaged by the end of the shuttle and force the release jaw inwardly, to release the wire. (See Figure 9.) However, when the feed shuttle advances to deliver the wire strand to the jaws 109 and 110, the nose of the collet 91 will strike the face of the jaw 110, forcing it inwardly into engagement with the jaw 109 and at the same time releasing the collet from its tapered seat.

15 The means for alining the feed and retrieving shuttles with the chuck mechanism for their successive operations will be described later.

The twisting and shearing mechanisms will now be described. Formed on the forward face 20 of the cross head 63, at one side of the boss 80, is a similar boss 117 to the center of which there is secured by a shouldered stud 118, a worm gear 119 of the same diameter as the gear 82. Secured to the outer face of the gear 119 are two 25 single lobe peripheral cams 120, 120 with their respective lobes spaced 180 degrees apart and adapted to be rotated by the gear 119. (See Figure 5.) Adjacent the gear 119, and in alignment with the gears 119 and 82, is another shouldered stud 121, upon which there is pivotally mounted the ends of oppositely disposed curved 30 shear blades 122, 122. The opposite faces of the shear blades are beveled in the customary manner to provide a cutting edge for the wire strands 35 after they are twisted together.

Adjacent its mean point, each of the blades is formed with a cam follower 123 adapted to engage its respective cam. Surrounding the stud 124 is a coiled spring 124 whose free ends 125, 40 125 engage the outer edges of the blades 122, 122 to force them together to shear the wire when simultaneously released by the cams 120, 120.

Formed on the cross head 63, and positioned 45 above each of the gears 82 and 119, are spaced bearings 126, 126 and 127, 127. Mounted upon a cross shaft 128 journaled in these bearings 126, 126 and 127, 127, and positioned between the bearings 126, 126, is a quadruple thread worm 50 129 in mesh with the worm gear 82; and between the bearings 127, 127, a single thread worm 130 in mesh with the worm gear 119. Accordingly, when the shaft 128 is rotated, the gear 82 will make four revolutions while the gear 119 makes 55 one revolution. It is thus evident that the strands of wire forming the binding tie will be firmly twisted together before the cams 120, 120 are rotated sufficiently to sever them. (See Figures 5, 6 and 7.)

60 The method of actuating the shuttles will now be described. Freely mounted on the projecting ends of the studs 102 of the yokes 101 in the shuttle tube 84, are links 131, 131 whose forward ends are pivotally connected to the outer ends 65 of lever arms 132, 132. (See Figure 1.) One of these lever arms for the feed shuttle 86 is secured to the inner end of the shaft 67, while the other lever arm 132 for the retrieving shuttle 87 is secured to the inner end of the shaft 68.

70 Secured to the outer end of the shaft 67 is another lever arm 133 to whose free end a link 134 is pivotally connected. Attached to the outer end of the shaft 69^a is a lever arm 135, shorter than the lever arm 133 and to which the link 134 is 75 pivotally connected. To the inner end of the

shaft 69^a there is keyed a bevel gear 136 adapted to be driven by a bevel pinion 137 whose hub extension is rotatably mounted within the bearing 71. Slidably mounted within the hub of the pinion 137 is the upper end of the vertical shaft 5 72. This shaft is formed with a keyway 138 extending the full length thereof and adapted to permit the sliding of the pinion 137 thereon when the cross head 63 is raised or lowered.

On the inner face of the frame structure 51 I 10 have provided a bearing 138^a for the lower end of the shaft 72, and to the latter, immediately above the bearing, there is secured a spiral gear 140 adapted to be driven by another spiral gear 139 keyed to a horizontal shaft 141. This shaft 15 141 is journaled in bearings 142, 142 formed on the inner face of the frame structure 51. Attached to the rear end of the shaft 141 is a bevel pinion 143 driven by a bevel gear 144 attached to a four-toothed gear 145 of another 20 Geneva gear drive. The gears 144 and 145 are freely mounted for rotation on a short stub shaft 146 secured to the rear vertical strut 52.

Secured to the outer end of the shaft 68 is a lever arm 147 to whose free end a link 148 is pivotally connected. Attached to the outer end of the shaft 70^a is a lever arm 149, shorter than the lever arm 147 and to which the link 148 is pivotally connected.

To the inner end of the shaft 70^a there is keyed 30 a bevel gear 150 that is adapted to be driven by a bevel pinion 150^a whose hub extension is mounted in the bearing 73. Slidably mounted within the hub of the pinion 150^a is the upper end of the vertical shaft 74. This shaft, like the shaft 35 72, is formed with a keyway 151 extending the full length thereof and adapted to permit the sliding of the pinion 150^a thereon when the cross head 63 is raised or lowered.

On the inner face of the frame structure 51^a 40 a bearing 152 is provided for the lower end of the shaft 74, and to the latter, immediately above the bearing, there is secured a spiral gear 153 adapted to be driven by another spiral gear 154 keyed to a horizontal shaft 155. This shaft 155 45 is journaled in bearings 156, 156 formed on the inner face of the rear frame structure 51^a. Attached to the rear end of the shaft 155 is a bevel pinion 158 driven by a bevel gear 159 attached to a four-toothed gear 160 of another 50 Geneva gear train 161. The gears 159 and 160 are freely mounted for rotation on a short shaft 162 secured to the rear vertical strut 52 of the structure 51^a.

The shafts 67 and 68 are intended to be alternately oscillated to advance and return the feed shuttle first, and then, after the descent of the binding head, to advance and return the retrieving shuttle. These operations are in definite timed relation, not only with each other but 55 also with respect to the shaft 78 by which the cross head or binding head is raised and lowered. This synchronized drive will now be described.

Keyed to the drive shaft 43 adjacent the frame 1 is a large gear 163 that is adapted to drive a 60 smaller gear 164 above it. The gear 164 is secured to the inner end of a short horizontal shaft 165 whose inner end is journaled in an inboard bearing 166 and its outer end in the frame structure 65 5 below the shaft 146.

Also mounted upon the shaft 165, adjacent the gear 164, is a pin disc 167 adapted to drive the four-toothed gear 145 when the pin 168 of the disc 167 engages one of said teeth. Secured to the face of the disc 167 is a lock plate 169 whose 70 75

periphery will enter one of the arcuate recesses in the gear 145, to lock the latter against rotation when disengaged by the pin 168. This mechanism constitutes a typical Geneva gear drive, and for each complete revolution of the shaft 165, the gear 145 will make one quarter of a revolution, and through the gears 143 and 144, 139 and 140, 136 and 137 the feed shuttle 86 will be projected across the binding head to deposit the strand of binding wire in the gripper mechanism and return to its starting position. Immediately following the operation of the feed shuttle mechanism, the binding head is lowered to straddle the stack of newspapers to be bound, and as it descends, additional wire is drawn through the feed collet to encompass three sides of the stack.

The mechanism for raising and lowering the binding head in timed relation with the shuttles will now be described. Meshing with the gear 19 is a larger gear 170 to whose outer face there is secured another four-toothed gear 171 of a Geneva gear drive 172.

Secured to the outer end of the shaft 165 is another pin disc 173 keyed to the shaft in fixed relation with the disc 167. Also attached to the inner face of the disc 173 is another lock plate 174 whose periphery will enter one of the arcuate recesses between the teeth in the gear 171, when the latter is disengaged by one of two diametrically opposite pins 175 and 176 carried by the disc 173.

As shown in Figure 1, the shaft 165 rotates counter-clockwise, and as soon as the pin 168 leaves the gear 145, the pin 175 carried by the disc 173 will engage one of the teeth of the gear 171 to impart a one-quarter revolution to it. Then, through the gears 19 and 170, the binding head will be lowered over the stack of newspapers to be bound. Immediately following the lowering of the binding head, the retrieving shuttle 87 will be projected to pick up the strand of wire held in the gripper mechanism 108.

The projection of the retrieving shuttle is accomplished in the following manner. Keyed to the shaft 43, adjacent the frame 6, is a large gear 177 similar to the gear 163 and adapted to drive a smaller gear 178, like the gear 164. The gear 178 is keyed to a shaft 179 whose inner end is journaled in an inboard bearing 180 and its outer end in the frame structure 51^a below the shaft 162.

Keyed to the shaft 179, adjacent the outer face of the gear 178, is a pin disc 181 in fixed relation with the pin discs 167 and 173. Also attached to the outer face of the disc 181 is a lock plate 182 whose periphery will enter one of the arcuate recesses between the teeth of the gear 180, when the latter is disengaged by a drive pin 183 carried by the disc 181, the gear 160, disc 181 and plate 182 constituting the Geneva gear train 161 previously referred to.

When the pin 175 leaves the gear 171, the pin 183 will engage one of the teeth of the gear 160 to turn it one-quarter of a revolution; and through the gears 158 and 159, 153 and 154 and 149 and 150, the retrieving shuttle will be projected to pick up the wire strand and return it to its starting position.

The ends of the wire strand are now ready to be twisted together, as previously described, by the rotation of the shaft 128, followed by a severing of the twisted strands. Secured to the outer end of the shaft 128 is a bevel pinion 184 adapted to be driven by a bevel gear 185, slidably keyed to the upper end of a vertical shaft 186. The hub

extension 187 of the gear 185 is journaled in a bearing 188 integral with the cross head 63.

To the lower end of the shaft 186 I have secured a spiral gear 190 adapted to be driven by another spiral gear 191 at right angles with it and keyed to the forward end of a horizontal shaft 192. (See Figure 10.) The shaft 192 is journaled in bearings 193, 193 provided on the inner face of the frame structure 51^a.

Attached to the rear end of the shaft 192 is a clutch disc 194 co-acting with another clutch disc 195 slidably keyed to the forward end of another shaft 196 in alignment with the shaft 192. The shaft 196, like the shaft 192, is supported in bearings formed on the inner face of the frame structure 51^a. Secured to the rear end of the shaft 196 is a beveled pinion 197 adapted to be continuously rotated by a bevel gear 197^a keyed to the inner end of the shaft 179.

The clutch discs 194 and 195 are normally held disengaged; but following the return of the retrieving shuttle 87 to its starting position, these discs are momentarily brought into driving engagement for a sufficient time to rotate the shuttles four revolutions to sever the twisted strands, as previously described. This engagement of the clutch discs is effected in the following manner.

Formed on the hub extension of the disc 195 is an annular recess 198 that receives therein the lower forked end of a lever arm 200. Integral with the upper pivoted end of the arm 200 is a cam follower arm 201 adapted to bear against the periphery of the pin disc 181. Now, following the disengagement of the pin 183 carried by the disc 181 from the gear 160, the cam follower will enter a depression 202 in the periphery of the disc and cause the clutch discs 194 and 195 to be brought into driving engagement.

In order to effect a proper alignment of the feed shuttle with the gripper mechanism when the binding head is raised, and the retrieving shuttle with the gripper mechanism when the binding head is lowered, I have provided a spiral rib 203 surrounding the vertical shaft 186. Therefore, when the binding head is lowered, the spiral rib 203 will engage a projection 204 on the frame 6 to rotate the shaft 186 sufficiently to transpose the position of the feed shuttle and the retrieving shuttle before the latter is projected. During the ascent of the binding head, the rib 203 carried by the shaft 186 will again cause the latter to be rotated sufficiently from the stopping position of the shaft 186 when the clutch is disengaged, to the position shown in Figure 5.

When the wrapped newspapers are discharged, they are deposited upon a table extension 205, extending rearward of the machine and supported by legs 206.

The means for applying a protective wrapping for the newspaper bundles will now be described. Extending transversely of the machine and journaled in the lower end of the front vertical members 4 of the frames 1 and 6, is a cross shaft 207 having secured thereto a wide pulley or roller 208. Extending transversely of the rear of the machine and journaled in the lower end of the rear vertical supports 5 of the side frames 1 and 6, is another cross shaft 209 having freely mounted thereon another wide pulley or roller 210. Movable around the pulleys 208 and 210 is a wide endless conveyor belt 211 which, at the rear end of the machine, passes under a supporting plate 212 carried by the bottom side rails 3, 3.

Keyed to the shaft 207 is a gear 213 that meshes with the gear 32. When the gear 32 is rotated, the gear 213 will cause the belt 211 to move forwardly a predetermined distance.

5 The plate 212 is adapted to support thereon a stack of discarded newspaper sheets whose overhanging portions are supported upon the belt 211. As the belt is advanced, the bottom sheet will be withdrawn by frictional contact with the belt and carried forwardly and deposited upon upwardly curving arms 214, 214. When the conveyor belts are advanced, the barbed stack fingers carried thereby will pick up the sheet of paper deposited upon the arms 214, 214 and carry it 10 forwardly to the stacking position below the fan. At this point the folded newspapers deposited therein will be encompassed by the wrapper and protected from damage by the subsequent handling of them.

15 Having described my invention, I claim:

1. In an apparatus of the type described, a supporting frame, a vertically reciprocable binder yoke mounted on said frame, conveyor means carried by said frame for conveying papers in 20 stacks below said binder yoke, a wire feed shuttle carried by one depending end of said yoke, a wire gripping and releasing device carried by the other depending end of said yoke, mechanism for operating the conveyor means to bring a stack 25 of papers to a stationary position under said binder yoke, means for projecting the feed shuttle, carrying a binding wire, to said gripping and releasing device, and for withdrawing it therefrom, leaving the binding wire over the stack 30 of papers which has been stopped below it, means synchronized with the conveyor-operating means for then bringing the binder yoke and wires down over said stack of papers, a retrieving shuttle carried by the feeding-shuttle end of said yoke, and mechanism for projecting the retrieving shuttle 35 under said stack of papers to draw the binding wire from the gripping and releasing device to the shuttle end of said yoke.

2. In an apparatus of the type described, a supporting frame, a vertically reciprocable binder yoke mounted on said frame, conveyor means carried by said frame for conveying papers in 40 stacks below said binder yoke, a binding wire feed shuttle carried by one depending end of said yoke, a retrieving shuttle carried by the same 45 end of said yoke, a wire gripping and releasing device carried by the other depending end of said yoke, and synchronized mechanism for successively moving the conveyor means to bring a stack 50 of papers beneath the binder yoke, projecting the feed shuttle over said stack and returning it, bringing the binder yoke down over said stack, and thereafter projecting the retrieving shuttle 55 under said stack to, and returning it from, the gripping and releasing device, to encompass the stack with the binding wire.

3. A bundling device for a paper bundling apparatus, comprising a binder yoke, reciprocable over a stack of papers, a tube mounted in one depending leg thereof, a feeding shuttle and a retrieving shuttle independently movable from said tube across the space between the legs of said yoke, a chuck carried by the other depending leg of said yoke, and jaws in said chuck to receive 60 one end of a wire carried to it by the feed shuttle, and to release said wire to the retrieving shuttle, 65

70 4. A bundling device for a paper bundling apparatus, comprising a binder yoke, reciprocable over a stack of papers, a tube mounted in one depending leg thereof, a feeding shuttle and a re-

trieving shuttle longitudinally movable in said tube, a chuck carried by the other depending leg of said yoke, wire gripping and releasing jaws in said chuck, and means for independently moving said feeding shuttle and retrieving shuttle 5 across the space between the legs of the yoke to said jaws, first the feeding shuttle to carry one end of said wire to said jaws, and then the retrieving shuttle to withdraw the wire from said jaws and return it to the tube leg of the yoke 10 under said stack of papers, after the binder yoke has descended over them.

5. A bundling device for a paper bundling apparatus, comprising a binder yoke reciprocable over a stack of papers, a tube mounted in one depending leg of said yoke, a feeding shuttle and a retrieving shuttle independently movable from said tube across the space between the legs of said yoke, a chuck carried by the other depending leg of said yoke, jaws in said chuck to receive 20 one end of a wire carried to it by the feed shuttle, and to release said wire to the retrieving shuttle, and means for rotating said shuttles to twist the ends of the wire gripped by said shuttles after they have returned to their positions 25 within said tube.

6. A bundling device for a paper bundling apparatus, comprising a binder yoke reciprocable over a stack of papers, a tube mounted in one depending leg of said yoke, a feeding shuttle and a retrieving shuttle independently movable from said tube across the space between the legs of said yoke, a chuck carried by the other depending leg of said yoke, jaws in said chuck to receive one 30 end of a wire carried to it by the feed shuttle, and to release said wire to the retrieving shuttle which carries it back to the tube under the paper stack, means for reciprocating said yoke, and means synchronized with the reciprocating movement of the binder yoke for rotating said shuttles 35 to twist the ends of the wire gripped by said shuttles when they have returned to the tube after the completion of the retrieving operation.

7. A bundling device for a paper bundling apparatus, comprising a binder yoke reciprocable 45 over a stack of papers, a rotatable tube in one depending leg of said yoke, a feeding shuttle and a retrieving shuttle independently movable from said tube across the space between the legs of said yoke, a chuck carried by the other depending leg of said yoke, jaws in said chuck to receive one end of a wire carried to it by the feed shuttle, and to release said wire to the retrieving shuttle which carries it back under the paper stack to the tube, and means for rotating said tube to bring 50 the feed shuttle, or the retrieving shuttle, into horizontal alignment with said chuck when it moves toward the latter.

8. A bundling device for a paper bundling apparatus, comprising a binding yoke reciprocable 60 over a stack of newspapers, a tube mounted in one depending leg of said yoke, a feeding shuttle and a retrieving shuttle independently movable from said tube across the space between the legs of said yoke, a chuck carried by the other depending leg of said yoke, jaws in said chuck to receive one end of a wire carried to it by the feed shuttle, and to release said wire to the retrieving shuttle which carries it back under the newspaper stack to the tube, means for rotating the shuttles to 65 twist the wire after the shuttles have returned to said tube, and cutting means through which the shuttles pass during their inward and outward movement, for cutting the wire strands after they have been twisted.

LOYE T. LOVETTE.
